CLAIM

We claim the ornamental design for a document tray, as shown and described.

DESCRIPTION

FIG. 1 is a perspective view of one embodiment of a document tray;

FIG. 2 is a top view of the document tray shown in FIG. 1;
FIG. 3 is a front view of the document tray shown in FIG. 1;

FIG. 4 is a side view of the document tray shown in FIG. 1, the opposite side of the document tray being the same as that shown in FIG. 4;

FIG. 5 is a rear view of the document tray shown in FIG. 1; and,

FIG. 6 is a bottom view of the document tray shown in FIG. 1.

The ornamental design which is claimed is shown in solid lines in the drawings. The broken lines in the drawings are for illustrative purposes only and form no part of the claimed design.
